UNITED STATES PATENT OFFICE.

JOSEPH DAW, OF QUEBEC, QUEBEC, CANADA, ASSIGNOR TO BROWN COMPANY, OF BERLIN, NEW HAMPSHIRE.

CHAIN SAW.

Original application filed September 11, 1924, Serial No. 737,147. Divided and this application filed August 5, 1925. Serial No. 48,405.

The invention relates to a chain saw as described in the present specification and illustrated in the accompanying drawings that form part of the same.

- 5 The invention consists essentially of the novel features of construction pointed out broadly and specifically in the claims for novelty following a description in detail of an acceptable form of the invention.
- 10 The objects of the invention are to facilitate the felling of trees particularly those of the smaller diameter used in the manufacture of paper stock; to insure celerity and efficiency; to enable the workman to pass 15 from tree to tree and thus cover large areas of timber in a comparatively short period in respect to other methods of felling; to simplify the mechanism in such devices and thereby reduce the cost of maintenance and 20 avoid delays in the matter of effecting repairs; to furnish a readily portable saw for various purposes such as for metal and stone cutting and other industrial or domestic work, and generally to provide a serviceable and durable saw easy to operate and 25 effective in its work.

In the drawings Figure 1 is a plan view of the assembled mechanism.

Figure 2 is a detail showing an enlarged 30 fragmentary detail of the saw.

Figure 3 is a cross sectional view of the chain saw on the line 3—3 in Figure 1.

Like numerals of reference indicate corresponding parts in the various figures.

35 Referring to the drawings the saw cutting teeth 10 are preferably formed in detached sets, each set being shown as having the projecting aligning lugs 13 and 14 from the one end and the bevelled aligning slots 15 and 16 at the other end in opposite sides.

The blade section 11 is reduced in thickness at the upper end 17 and these reduced ends form the arc-shaped driving teeth 18, 45 which are intended to be engaged by corresponding sprocket wheels.

The chain sections 17 are formed with the link slots 19 and 20 from the ends respectively, these slots being part circular and 50 cut away at the edges 21 and having flaring open ends 22.

The link bars 23 forming the joint members in connecting the several units to make

an endless chain are inserted in the slots 19 and 20 of different units and the enlarged 55 rounded ends 24 and 25 of said bars which are slightly grooved in the centre of their peripheries and trimmed at the edges, are forced into the convexly walled slots 19 and 20, to hold the links and chain sections flexibly together.

It will now be seen that the endless chain formed by the blade sections presents an outer cutting edge for the complete length of the chain and a toothed back forming 65 an operating back also for the complete length of the chain on the inner side.

In the operation of this saw it will thus be seen that when it is being driven the sections of the chain saw will always be 70 maintained in constant alignment by the aligning lugs 13 and 14. It will also be seen that when one of the chain sections has been broken it can very easily be 75 changed and thus very little time is lost in both the cutting and the repairing operations.

What I claim is:—

1. In a power saw, a portable frame containing a gear and sprocket driving mechanism, and a chain saw mounted in said frame and having backs to the teeth engaging said sprocket mechanism and links joining the teeth members through disk ends slightly grooved to fit in the teeth. 85

2. In a power saw, a portable frame containing a gear and sprocket driving mechanism, and a chain saw mounted in said frame and having sections formed on the outside with cutting teeth, aligning slots 90 and lugs, link bearing slots having flaring outer ends and bar links having enlarged ends bearing said link.

3. In a power saw, a portable frame containing a gear and sprocket driving mechanism, and a chain saw mounted in said frame and having linked and centrally slotted sections with cutting teeth on the one side and driving teeth on the other and engaged by said sprocket mechanism, said 95 links joining the teeth members through disk ends grooved and coacting with convex walls in said slots.

4. In a power saw, a portable frame containing a gear and sprocket driving mechanism and a chain saw mounted in said 100

frame and comprising sectional saw pieces and links mounted in part circular slots therein and joining the teeth members through disk ends in convex and concave joints.

5. In a power saw, a portable frame containing a gear and sprocket driving mechanism, and a chain saw in said frame and formed of teeth sections having link bearing slots extending inwardly from each end and bevelled at the edges and teeth projecting from the backs, and links joining the teeth members through disk ends in convex and concave joints.

10. In a power saw, a portable frame containing a gear and sprocket driving mechanism, a chain saw mounted in said frame and comprising cutting teeth on the one side and sprocket teeth on the other and links joining the teeth members through disk ends in convex and concave joints.

15. In a power saw, a portable frame containing a gear and sprocket driving mechanism, a chain saw mounted in said frame and comprising a plurality of saw members, each member having aligning projections and slots adapted to maintain the adjoining sections flush with one another, and

links joining the teeth members through disk ends in tongued and grooved joints.

20. In a power saw, a portable frame containing a gear and sprocket driving mechanism, a chain mounted in said frame and comprising a plurality of saw members, each member having bevelled lugs flush with the face at one side and bevelled slots at the other side for the lugs from an adjoining member to bring the faces of the neighboring member flush and rigid one with the other, and links joining the teeth members through disk ends in tongued and grooved joints.

25. In a power saw, a portable frame containing a gear and sprocket driving mechanism, a chain saw mounted in said frame and comprising a plurality of saw members having their backs of reduced thickness and forming a projecting tooth, a follower bar of the same thickness as the saw members and having a slot receiving said tooth and links joining the teeth members through disk ends in tongued and grooved joints.

30. Signed at Quebec this 20th day of March 1925.

JOSEPH DAW.
